CLAMP FOR ROOFS

Filed Dec. 31, 1921

2 sheets-sheet 2

UNITED STATES PATENT OFFICE.

CHARLES COURTNEY WHITE, OF OCEAN SPRINGS, MISSISSIPPI, ASSIGNOR OF ONE-
THIRD TO LOUIS BRAUN, OF BILOXI, MISSISSIPPI.

CLAMP FOR ROOFS.

Application filed December 31, 1921. Serial No. 526,093.

To all whom it may concern:

Be it known that I, CHARLES C. WHITE, a citizen of the United States, and a resident of Ocean Springs, in the county of Jackson 5 and State of Mississippi, have invented a new and Improved Clamp for Roofs, of which the following is a description.

The general object of my invention is to provide clamps for use on roofs in various 10 positions at the joints, at the overlapped shingles, at the peak, and as an edging for the roof, whereby important results are obtained to make the roof water-tight and keep it from buckling or warping, as well as to 15 prevent nails when over-driven from damaging the roof, and in addition, the roof is given a better appearance by disposing the nails in line doing away with irregular rows 20 of nails and relieves the nails of strains.

Reference is to be had to the accompanying drawings forming a part of this specification, it being understood that the drawings are merely illustrative of practical examples of the invention.

Figure 1 represents my improved clamp applied to the roof at the peak at the joints of the side edges of the shingles, and to the lower edge of the roof;

Figure 2 is an enlarged transverse vertical section on the line 2-2, Figure 1;

Figure 3 is an enlarged elevation of the strip for the joints at the side edges of the shingles;

Figure 4 is an enlarged transverse vertical section on the line 4-4, Figure 3;

Figure 5 is an enlarged vertical section on the line 5-5, Figure 3;

Figure 6 is an inverted perspective view of a fragment of the joint clamp plate shown in Figure 4;

Figure 7 is an enlarged vertical section on the line 7-7, Figure 1;

Figure 8 is a vertical section showing a clamp of the form illustrated in Figure 7 but employed at the lower edge of a shingle and overlapping a shingle beneath;

Figure 9 is a vertical section of the upper portion of the clamp shown in Figures 1, 3 and 4 with a fabric layer;

Figure 10 is a view similar to Figure 9 showing a modification of the clamp in Figure 9;

Figure 11 is a vertical section similar to Figure 7 but showing a clamp similar to that

of Figure 7 adapted for receiving two superposed shingles or roof boards at the lower edge. 55

In carrying out my invention I provide clamp plates 10 adapted to overlie a joint at the side edges of two shingles of a layer. 60 Said plate has an individual clamp 11 at its upper end U-shaped in vertical section as best seen in Figure 5 and presenting a top member 12 and an under member 13, the former extending beyond the under plate. 65 At the upper edge of the member 12 at the under side thereof is a flange 14 adapted to effect a line contact with a shingle *a* therebeneath. Similarly, a flange 15 is formed at the edge of the under member 13 at the 70 under side of the latter to effect a contact with the overlapped portion of the next lower shingle. Said individual clamp 11 is integral with the plate 10, the under member being continuous with the body of the 75 plate 10 at the flange 15. Similarly, at the lower end of the plate 10 the same is returned on itself at the under side to provide an individual clamp 16, the under member 17 terminating in a depending edge flange 18 to 80 effect line contact with the shingles beneath. Nails *b* may be driven through the plate 10 along the sides, nail holes being provided for the purpose as shown in Figure 6 so that the nails will be in straight rows. Also, the 85 plate 10 prevents the nails when over-driven from damaging the shingles and they will form tight closure at the nail holes instead of making for leaks when driven directly through shingles particularly when the nail 90 does not strike the roof frame beneath. At the peak of the roof I provide a clamp presenting opposite side members 19, 20 adapted to lie at opposite sides of the ridge, said plates having respectively at their lower 95 edges at the under sides of said members flanges 21 and 22 to effect line contact with the shingles *a* therebeneath. The various flanges 14, 15, 18, 21 and 22 embed themselves in the shingles so that the members 100 on which the flanges are formed will lie flat on the shingles. In order to cover the joint *c* formed by the shingles at the ridge I form integrally with the sides 19, 20 an intermediate hollow ridge member 23 by bending 105 the material twice at right angles, the said ridge member at one side being continuous and in the plane of one of the side members

as 19, that is to say, the material is carried at the upper end of the one side member 19 beyond the plane of the opposite member 20 and returned to be continuous with said opposite side member 20. Reverting to the 5 plate 10 for the side edge joints of the shingles α , it will be observed that the same is formed with longitudinal side flanges 24 at the under side of the plate to form a line 10 contact at opposite sides with the adjacent shingles and embed themselves in the shingle material when the nails are driven home.

In Figure 7 is shown a clamp 26 which is similar to the clamp 16 only formed independently of any joint plate 10 and adapted to be applied individually to the shingles at the lower edge of the roof. Said clamp 26 is of U-shape in vertical section to present upper and under members, the upper member 20 extending beyond the under member so that nails e driven through the upper member adjacent to the edge thereof will clear the under member in engaging the roof frame. The upper member is provided 25 at the upper edge thereof with a depending flange 27 and the under member terminates in a depending edge flange 28 to embed themselves respectively in a shingle and a roof frame.

30 In Figure 8 is shown a clamp 11 a similar to the clamp 11 presenting an upper member 12 a and an under member 13 a terminating in edge flanges 14 a , 15 a depending at the under side. Thus, the clamp 26 takes the place of the clamp 16 and the clamp 11 a takes the 35 place of the clamp 11 when the clamps are to be applied to the lower edges of the shingles without a joint clamp plate 10.

40 In Figure 9 the clamp 11 with the features 13 to 15, as described, is shown and in addition the layer of fabric 25 in the under surface. Said fabric extends beyond the bead 15 to be turned into the interior of the U-shaped clip, the extent of the turned-in 45 portion of the fabric varying in practice according to the extent of the surface of the clamp 11 to be covered thereby.

50 In Figure 10 is shown a clamp 11 b corresponding with the clamp 11 but instead of being formed continuous with a plate as 10, said clamp is secured by soldering, brazing, or the like to a similar plate 10 b which abuts 55 against the flange 15 b corresponding with the flange 15. Said clamp 11 b has an upper plate 12 b with a flange 14 b and an under plate 13 b having flange 15 b , said parts corresponding with the similar features of the clamp 11.

60 In Figure 11 is shown a clamp 26 c corresponding with the clamp 26 with respect to being of U-shape in vertical section and having depending flanges 27 a , 28 a , said clamp

26 a , however, being of a size to constitute the edge portion of two super-posed shingles.

I would state in conclusion that while the 65 illustrated examples constitute practical embodiment of my invention, I do not limit myself strictly to the exact details herein illustrated, since, manifestly, the same can be considerably varied without departing 70 from the spirit of the invention as defined in the appended claims.

Having thus described my invention, I claim:

1. A roof clamp of U-shape presenting 75 upper and lower members and adapted to receive between the two an edge portion of the roof element, the upper member extending beyond the lower member for more effectively clamping the upper surface of said 80 roof element.

2. A roof clamp of U-shape presenting 85 upper and lower members adapted to receive between the two an edge portion of the roof element, said upper and lower members each 90 having a flanged edge extending downwardly to effect a contact with the roof material therebeneath, said upper member extending beyond the lower member for more effectively engaging the upper surface of 95 said edge portion.

3. As a new article of manufacture, a 95 plate adapted to be applied to a roof over a joint formed by the opposite side edges of shingles, said plate having clamps at the upper and lower edges adapted to receive the lower edges of adjacent overlying shingles.

4. As a new article of manufacture, a 100 plate adapted to be applied to a roof over a joint formed by the opposite side edges of shingles, said plate having clamps at the upper and lower edges adapted to receive the lower edges of adjacent overlying shingles, the side edges of said plate between said 105 clamps having flanges at the under side of the plate to effect line contact with the roof material beneath.

5. A clamp adapted to be applied to adjacent ends of roof elements comprising a 110 strip of metal presenting a socket at one side and a socket at the opposite side for receiving the lower edges of adjacent overlying roof elements.

6. A clamp adapted to be applied to a 115 roof area comprising a strip of metal presenting a socket at each end adapted to slidably receive the edge portion of adjacent overlying roof elements, said sockets being oppositely disposed and formed at their edges with downwardly extending flanges 120 adapted to embed themselves in the material therebeneath.

CHARLES COURTNEY WHITE.
